Patented Apr. 10, 1917.

UNITED STATES PATENT OFFICE.

JOHN WILLIS FOWLER, OF HENNIKER, NEW HAMPSHIRE; HERBERT E. FOWLER
ADMINISTRATOR OF SAID JOHN WILLIS FOWLER, DECEASED.

MILK-CAN.

1,222,279.

Specification of Letters Patent. Patented Apr. 10, 1917.

Application filed February 24, 1916. Serial No. 80,104.

To all whom it may concern:

Be it known that I, JOHN WILLIS FOWLER, a citizen of the United States, residing at Henniker, in the county of Merrimack and 5 State of New Hampshire, have invented a new and useful Improvement in Milk-Cans, of which the following, together with the accompanying drawings, is a specification.

The object of my present invention is to 10 provide a cheap and efficient means of closing cans in which milk is usually shipped, and sufficiently durable to withstand the rough usage incident to transportation.

In the accompanying drawings I have 15 shown so much of a milk can as is necessary to illustrate the nature of my present invention, and in which—

Figure 1 is a side elevation of the upper portion of a milk can provided with my improved closing device, and

Fig. 2 is a central sectional view of the same on the plane of the broken line 2—2, Fig. 1.

Similar reference characters refer to similar parts in both figures.

In carrying my invention into practice, I construct the body 1 of the can of sheet metal in the usual manner and of any size desired, and provided at the top with a 30 narrow flange 2 to which I attach a metal neck 3, preferably of malleable iron, and suitably attached to the flange 2 by rivets 4. The neck 3 is recessed at 5 upon its outer surface to receive the flange 2 flush with the 35 outer surface of the neck. The joint between the neck 3 and the flange 2 may be closed at its lower edge, if desired, by means of solder 6. The upper end of the neck 3 is provided with an interior annular rib 7 extending up- 40 wardly, and an exterior annular rib 8 extending some distance above the rib 7. The rib 7 is turned or ground to a smooth surface lying in a uniform plane to form a seat for a cover 9, which is provided on its under 45 surface with an annular rib 10 which is also ground to a smooth and uniform plane adapted to contact with the rib 7.

The metal neck 3 is preferably recessed on diametrically opposite sides 11 to receive the 50 ears 12 which are attached at their upper ends by rivets 13 and at their lower ends by rivets 14, the latter rivets 14 passing preferably through the flange 2. The ears 12 are

raised to form a boss 15 to provide a space 16 between the boss 15 and the outer surface 55 of the neck 3. The bosses 15 are each provided with a central hole 17 to receive the ends of a wire 18 which is extended around the can to form a lever handle 19. Near the ends of the wire 18 it is coiled, as shown 60 at 20, 20, in order to form an eye 21 to receive the ends of an elastic wire bail 22, capable of swinging in the eyes 21 over the top of the cover 9 into engagement with the top of a triangular rib 23 extending up- 65 wardly from the top of the cover. By raising the lever handle 19, the eye 21 will be swung from the position shown in Fig. 1 to- 70 toward the left, thereby decreasing the distance between the eye 21 and the top of the 70 rib 23. This movement of the handle 19 loosens the bail 22 so it may be swung over the edge of the cover 9 against the side of the can, thereby allowing the cover to be re- 75 moved. By replacing the cover and again swinging the bail over the top of the rib 23, the handle 19 is depressed, bringing the eye 21 into its normal position, as shown in Fig. 1, and thereby increasing the distance be- 80 tween the eye and the top of the rib 23, 80 which serves to draw the bail 22 tightly over the rib and hold the cover closely upon the neck of the can. The arrangement of the bail 22 and lever handle 19 with its eyes 21 form no part of my present invention, 85 however, the same device being now in com- mon use for holding the covers upon fruit jars and similar receptacles.

The lever handle 19 is, however, provided at its center with a loop 24 which, when the 90 handle 19 is depressed in the position shown in Fig. 1, embraces a staple 25 attached to the side of the can, allowing the hasp of a padlock 26 to be inserted through the staple for the purpose of locking the handle 19 in 95 its depressed position, thereby securely af- fixing the cover 9 in position. The cover 9 is extended beyond the rib 10 over the top of the rib 8 and is provided at its outer edge with a depending lip 27 to guard against the 100 access of dirt or other extraneous matter into the space above the rib 8. A free space is provided between the neck 3 and the cover 9, except at the contacting surfaces of the ribs 7 and 10, thereby avoiding the necessity 105 of finishing the opposing surfaces of the

cover and neck except upon the ribs 7 and 10. The space 28 between the cover and the rib 8 may also be utilized to receive a gasket or suitable packing, if desired, to hermetically seal the can.

5 I claim:

- 10 1. The combination with a sheet metal body, of a cast metal neck attached at its lower edge to the metal body and having its upper edge increased in thickness and provided with an interior annular rib extending upwardly, and an outer rib spaced from said interior rib but having its face at a higher elevation than said interior rib, and
- 15 2. a cover having a rib on its lower surface resting on said interior rib and extending

over said outer rib, with a depending lip on its outer edge.

2. The combination with a sheet metal body, of a cast metal neck attached at its lower edge to said body and having recessed sides, ears attached to said neck and held in said recesses, a cover resting on said neck, means pivotally held in said ears for retaining the cover on said neck, and means on the body of the can below said neck for engaging said cover retaining means.

JOHN WILLIS FOWLER.
